DESIGN FOR A LADLE

Roberta H. Abel, Jeffersontown, Ky.

Application December 22, 1945, Serial No. 124,958

Term of patent 7 years

(Cl. D44—29)

To all whom it may concern:

Be it known that I, Roberta H. Abel, a citizen of the United States, residing at Jeffersontown, in the county of Jefferson and State of Kentucky, have invented a new, original, and ornamental Design for Ladle, of which the following is a specification, reference being had to the accompanying drawing, forming a part thereof.

In said drawing:

I claim:

The ornamental design for a ladle, as shown.

ROBERTA H. ABEL.
